UNITED STATES PATENT OFFICE.

FRANK F. HOWE, OF MARIETTA, OHIO.

TELEPHONE-RECEIVER SUPPORT.

No. 831,348.

Specification of Letters Patent.

Patented Sept. 18, 1906.

Application filed March 31, 1906. Serial No. 309,217.

To all whom it may concern:

Be it known that I, FRANK F. HOWE, a citizen of the United States, and a resident of Marietta, in the county of Washington and 5 State of Ohio, have invented certain new and useful Improvements in Telephone-Receiver Supports, of which the following is a specification.

My invention is an improvement in telephone attachments, being in the nature of an improvement in the means for supporting the telephone receiver and transmitter; and the invention consists in certain novel constructions and combination of parts, as will 15 be hereinafter described and claimed.

In the drawings, Figure 1 is a side elevation, parts being broken away and parts being shown in section, of an apparatus embodying my invention. Fig. 2 is a detail 20 elevation of the inner side of the base. Fig. 3 is a detail top plan view of the receiver-support. Fig. 4 is a detail side elevation of the holder for the receiver. Fig. 5 is a detail 25 side view of the receiver. Fig. 6 is a detail top plan view of the receiver and its holder. Fig. 7 is a bottom plan view of the transmitter and its support.

In carrying out the invention I employ a hollow-base wall-bracket A, having a chamber or recess A' in its rear side receiving the 30 spring connections a, a', and A², and it is also provided in its front side with a laterally-elongated slot A³, through which projects a lug on the rear end of the transmitter-support 35 port for operating the spring A², as will be presently described. The springs a, a', and A² are secured to the base A and are properly insulated, as shown, and are suitably connected with the line-wires, so that when the 40 transmitter-support is in its normal position the telephone will be cut out of the circuit and when said transmitter-support is moved to one side or the other in adjusting the transmitter or speaking-tube to position for 45 use the telephone will be cut into the line, as will be understood by those skilled in the art. The bracket A is also provided with forwardly-projecting lugs A⁴, A⁵, and A⁶, arranged one above the other, the upper lug A⁴ 50 and the lower lug A⁶ being spaced sufficiently away from the intermediate lug A⁵ to receive between them the receiver-support B and the transmitter-support C. The intermediate lug A⁵ is provided with a vertical opening or 55 slot a⁵, which is elongated laterally to permit

the movement of the upwardly-projecting pin on the transmitter-support C in the operation of the invention. The receiver-support B comprises the main or inner arm B' and the outer arm B², pivoted to the main 60 arm at B³ and receiving the tube B⁴, which carries the receiver 5 at its outer end and is telescoped on the outer arm B², as will be understood from Figs. 1, 4, and 6 of the drawings. The main arm B' is pivoted vertically 65 at b' between the lugs A⁴ and A⁵ and has its rear end or extension in rear of the pivot b' forked or slotted at 1 to receive the pin projecting from the transmitter-support. At its outer end the main arm B' of the receiver- 70 support is slotted at 2 to receive the disk 3 at the inner end of the outer arm B², the parts being pivoted on the clamp-screw 4, which may be tightened to secure the parts B' and B² in any desired adjustment.

The outer arm B² receives the tube B⁴, which telescopes on the arm B² and is provided with a slot B⁵, through which projects a pin B⁶ from the arm B², the pin B⁶ being preferably hooked, as shown in Fig. 6, so it may 80 support the wires running from the receiver. The slot B⁵ is sufficiently long and wide to permit an adjustment of the tube B⁴ longitudinally and circumferentially upon the arm B², the circumferential adjustment of the 85 tube B⁴ permitting the adjustment of the receiver in use to either the right or left ear, as will be understood from full and dotted lines, Fig. 6, of the drawings.

The receiver 5, which is preferably a watch- 90 case-receiver having the connections 6 on its back, as shown in Fig. 5, is secured to an upright wing 7 of a flat bar 8, which is pivoted at 9 in a slot in the outer end of tube B⁴, so the receiver may be adjusted on the pivot 9, 95 an inclined wall 10 (see Fig. 6) limiting the adjustment of the receiver, as will be understood from the drawings.

The cords or wires running from the receiver 5 may rest in the hook B⁶ and extend 100 thence back to the base and be suitably connected, as will be understood by those skilled in the art. It will be noticed that the pivoting of the inner arm of the receiver-support to the base permits the swinging of 105 the receiver laterally back and forth, the pivot B³ between the inner and outer arms B' and B² permits a vertical adjustment of the receiver, and the telescopic construction of the outer 110 section of the receiver-support permits a lon-

itudinal and rotary adjustment of the receiver, as will be understood from the drawings and foregoing description.

The supports B and C stand normally out straight and are held yieldingly in said position by springs D, bearing on the opposite sides of one of said supports. In the drawings these springs are shown on opposite sides of the support C. (See Fig. 7.) Lugs 10 A⁷ on the base A on opposite sides of the support B limit the lateral movement of the inner arm B' and give a solid stop against which to rest the support when moved in either direction to position for use. The contact-spring A² extends over the slot A³ in the bracket and is suitably bent or curved to be operated by the lug C⁵ at the rear end of the transmitter-support.

The transmitter-support C has the inner section C' and the outer section C² jointed horizontally at C³, so the transmitter may be raised and lowered to any desired position. The inner section C' is pivoted at C⁴ to the bracket and is provided in rear of said pivot 20 with a lug C⁵, projecting through the slot A³ in the bracket and operating upon the spring A². This section C' of the support C also has an upwardly-projecting pin C⁶, which extends through the slot A⁵ and into the slot 1 25 of the support B, so that the lateral movement of either of the supports B and C will effect a reverse movement of the other support. It will be noticed that the pivots of the supports B and C are so located that 30 when the receiver-support B is moved but slightly to one side or the other it effects a considerable movement of the transmitter-support in the opposite direction, the leverage at the rear end of the receiver-support 35 being greater than the leverage between the pin C⁶ and the pivot of the transmitter-support, and as the transmitter-support is moved on its pivot in one direction or the other it makes and breaks the electric connections by the action of the lug, &c., as before described.

The bracket A is provided at its lower end with a pin A⁸, which is loosely held, and may be raised to be engaged by either side of the 50 transmitter-support when the same is moved out of normal position to keep the phone temporarily cut in, and when the transmitter-support is moved slightly, as by the pressure of the ear to the receiver, the pin A⁸ will drop down out of the way.

The transmitter E, having the speaking-tube or mouthpiece E', is pivoted vertically at E² to the outer end of the section C² of the receiver-support, so the transmitter may be 55 rocked to one side or the other in adjusting it for use when the right or left ear is applied to the receiver. A spring F (see Fig. 7) holds the transmitter normally inclined to one side or the other, being shown in Fig. 7 in position 60 to hold the tube normally inclined to the left

or in proper position when the left ear is applied to the receiver. A spring connection G is attached to the transmitter at one side of its pivot E² and extends thence to and is connected with the bracket A. As shown, the connection is a spring-wire coiled between its ends to form a spring and straight at its ends to permit the up-and-down movement of the transmitter. This spring will operate by the movement of the support C from the position 75 shown in Fig. 7 in the direction of the arrow to hold the transmitter around, bringing the speaking-tube to the proper angle in relation to the receiver when the right ear is applied to the receiver, and will overcome the tension 80 of the spring F, before described. When the support C is in normal position or swung in the reverse direction from the arrow in Fig. 7, the spring connection G will hang slack. The support C is preferably made hollow, as 85 shown, to permit the passage of the spring connection G and of the electrical connecting-wires leading to the transmitter.

The connection between the receiver and the hollow tube B⁴ is preferably a tight-fitting spring-joint, so the receiver may be shifted to and held in any desired adjustment relative to the said tube B⁴, as will be understood from Figs. 4 and 5 of the drawings.

I claim—

1. The improvement in telephone attachments herein described, comprising a base or bracket having forwardly-projecting lugs and chambered or recessed for the contact-springs, a receiver-support, and a transmitter-support pivoted between the lugs of the base, one of said supports being provided with a projecting portion for operating the contact-springs, intermediate devices between the transmitter and receiver-supports whereby the movement of one on its pivot will operate the other, the receiver support being provided with an inner or main arm and with an outer arm pivoted to the main arm and supporting the receiver proper, a transmitter pivoted to its support, and spring devices operating upon the transmitter whereby to shift the same by the swinging of the support on its pivotal connection with the base or bracket, substantially as set forth.

2. The combination with the bracket or base, of a receiver-support pivoted thereto, a transmitter-support pivoted to the base or bracket, intermediate devices between the receiver and transmitter supports whereby the shifting of one will shift the other, the lever relation between the two supports and the intermediate devices being such as to 120 effect by a slight movement of one of the supports a corresponding greater movement of the other support, substantially as set forth.

3. The combination with a pivoted re- 130

- ceiver-support and a pivoted transmitter-support, of an intermediate connecting device between the two supports, the said device being secured to one of the supports and 5 engaged with the other support at different distances from the pivots of the respective supports whereby to secure a varying movement of the two supports, substantially as set forth.
- 10 4. The combination with the bracket or base, of a receiver - support pivoted thereto, and a transmitter-support also pivoted thereto, one of said supports having a longitudinally-slotted portion or fork and the 15 other support having a projecting pin entering the slotted portion or fork of the other support, substantially as set forth.
5. A telephone attachment having a receiver-support movable from side to side, a 20 transmitter-support movable from side to side, means whereby said movement of one of said supports will effect a reverse movement of the other support, and means whereby such movement of one of the supports 25 may make and break the electric connection, substantially as set forth.
6. The combination in a telephone attachment of a receiver-support adapted to move from side to side, a transmitter-support 30 adapted to move from side to side, and means whereby the movement of one of said supports from side to side will effect a reverse movement of the other support.
7. The combination with the bracket or 35 base, of a receiver-support pivoted thereto, a transmitter-support pivoted thereto, one of said supports having an extension in rear of its pivot, and devices connecting with the other support in advance of its pivot and operating upon the rear extension of the other support whereby the movement of one of said supports in one direction will effect a movement of the other support in the reverse direction.
- 40 45 8. The combination with the base or bracket and the transmitter-support pivoted thereto and adapted to move from side to side, of a drop-pin loosely held in the bracket below the transmitter-support and adapted to be shifted upwardly alongside 50 said support whereby to temporarily leave the phone cut into circuit, substantially as set forth.
9. In a telephone attachment the combination with the bracket and the supporting- 55 arm pivoted thereto, of a latch loosely connected with the bracket and adapted to be shifted alongside the support to hold the same temporarily in any desired adjustment and to drop by gravity out of engagement 60 with the said support, substantially as set forth.
10. The combination with the receiver, of a bar projecting therefrom and having a flat extremity, and a receiver-support having a 65 slot receiving said flat extremity, and means for pivoting the same within the slot, the flat extremity fitting tightly within the slot whereby the receiver may be tipped to any suitable adjustment and secured therein 70 until forcibly readjusted, substantially as set forth.
11. The combination with the bracket and a transmitter-support pivoted thereto, of a transmitter pivoted to said support, a spring 75 for pressing the transmitter in one direction and a second spring opposing the first and connecting the transmitter with the bracket whereby the shifting of the transmitter-support on its pivotal connection with the bracket may automatically adjust the transmitter relatively to its support.
12. The combination with a pivoted transmitter-support and a transmitter jointed to said support, of a spring for holding said 85 transmitter in normal position, and a spring connection between the transmitter and its support whereby to automatically adjust the transmitter relative to its support when the latter is moved on its pivot, substantially as 90 set forth.

FRANK F. HOWE.
